DECANTATION APPARATUS AND METHOD

John Zollinger, Oakhurst, N. J.

Application June 2, 1932, Serial No. 614,968

14 Claims. (Cl. 210—55)

This invention relates to decantation apparatus and methods.

One object of this invention is to provide a device for the continuous separation of a finely divided solid from a liquid together with the removal of undesirable light constituents of the liquid, the device having improved means for expelling or draining liquid from the solids removed from the liquid by compression or compacting of the solids as removed.

Another object of the invention is the provision of an improved method of decantation, wherein a portion of a mass of settled solid is removed from along said mass and the removed portion constantly moved upwardly out of the liquid while subjected to a suitable or its own weight for compressing the liquid out of the mass portion so elevated, and additional solids being continuously added to the bottom of the upward moving portion preferably so as to urge the latter upward, as in a scooping action.

Another object of the invention is to provide improved apparatus and method utilizing scoop elements such that, not only is the machine as a whole continuous in operation, but each individual scoop element is also continuous in operation.

Another object of the invention is the provision of a decantation apparatus whereby the foregoing method can be advantageously practised, and which apparatus shall be relatively simple in construction, easy and convenient in operation, reliable and efficient to a high degree in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawing, wherein like parts are designated by the same reference characters throughout the several views.

In the drawing:

Figure 1 is a top plan view of a device embodying the invention, with certain parts removed.

Fig. 2 is a vertical sectional view taken on line 2—2 of Fig. 1.

The advantages of the invention as here outlined are best realized when all of its features and instrumentalities are combined in one and

the same structure, but, useful devices may be produced embodying less than the whole.

It will be obvious to those skilled in the art to which this invention appertains, that the same may be incorporated in several different constructions. The accompanying drawing, therefore, is submitted merely as showing the preferred exemplification of the invention.

Generally described, this invention provides an apparatus and method of decantation which depends not solely upon drainage for separation of the solids from the liquid, but wherein the primary principle is that scoop means are employed moving along a mass of settled solids within a liquid and causing a continuous upward movement of the solids along the scoop means. This movement is possible because of the resistance of the settled solid mass at the lower end of the scoop means, creating an upward force along the latter whereby a movement under pressure is effected. More particularly, the solids moving along the scoop are subject directly to their own weight plus the frictional resistance of the movement. In this manner the solids are elevated, preferably continuously, out of the liquid, and the liquid is simultaneously expressed from the scooped mass both above and below the level of the liquid that is being decanted. The angle of the scoop bears a definite relation, since it must be such as to substantially meet the angle of repose of the scooped mass, and may be either greater or less, depending upon numerous factors, among which may be mentioned the size and specific gravity of the solid particles, the speed at which the decantation occurs, the degree to which the water is to be removed from the solids, as influenced by pressure and hence frictional resistance, the degree to which reliance is placed on ordinary drainage and the time therefor, and other like factors. As is well known the angle of repose is different for different materials, and will naturally be affected by the degree of wetness of the solids. At the point where the solids are removed from the scooped means, the latter may have a unitary or independent means that may be so inclined as to direct any drainage away from the direction of removal. My invention provides continuous decantation, with a slight agitation for releasing impurities of the solids.

An especial feature of the invention is that not only is the machine continuous, but each scoop element is also continuous in operation, affording superior decantation. The inlet may be arranged so as not to disturb the settled solids, and the liquid may be withdrawn at a point below

the upper part of the scoop means. A primary feature of the principle of operation of the invention is that the drainage is so taken care of as not to affect the solids that are being removed.

5 The invention may be used for discarding any undesired solids whether the same be light or heavy; for example, loam or clay.

Referring in detail to the drawing, 10 denotes a device embodying the invention. The same 10 may include a settling compartment of any suitable form or character, preferably round, and having a side wall 11 that may taper downward slightly. The bottom wall 12 may be arranged at any desired angle but is preferably horizontal. 15 The compartment may have suitable bottom and side wall bracing 13, 14. The top of the compartment may be simply open as shown.

Disposed in the compartment is a suitable rotor 15 which may have an upright axis that is preferably vertical. This rotor may be mounted and driven in any feasible manner, as by a shaft 16 journaled in bearings 17, 18 carried by a frame 19 supported, for example, upon the braces 14. A gear 20 may be connected to said shaft and rotated by a pinion 21 mounted on a shaft 22 to which power may be furnished from any suitable source.

The rotor 15 may include a hub portion 23 to which may be secured a cross frame 24 connected 30 to the shaft 16. Said rotor may be made of cast or sheet metal and may form a unitary structure that may be rotated clockwise as shown.

The rotor 12 may include an upper wall or floor 25 which may be round or of other suitable 35 form and preferably spaced from the wall of the chamber. Said wall is preferably downwardly concaved toward the center of the rotor, and the angle of the concavity may be 30 degrees with the horizontal, but the angle may also be greater 40 or less, say 45 degrees or 15 degrees. Said wall may be connected to the hub 23 at any suitable point, preferably at 26 in spaced relation to the upper end of the hub which may thus form an inner rim flange 27 for said wall.

45 Extending in downward relation are one or more scoop elements 28 movable in any desired path, preferably circularly, as by being made a part of the rotor 15. For example, six scoop elements may be provided equally spaced angularly and connected to the wall 25 that may have corresponding openings 29 communicating therewith. These scoop elements may be disposed at a suitable acute angle with a horizontal plane, for instance, they may be elongated in their direction of travel at an angle of 30 degrees to the horizontal, but this angle may be as great as 90 degrees and as small as 15 degrees. Generally, the angle will depend upon the angle of repose of the solid materials that are being removed, and may be equal, greater or less than the same. 50 If the angle is less than the angle of repose, the solids will be easily elevated; if the angle be greater, the frictional resistance in the movement of the solids along the scoop elements will be increased, and the particles of the solids on the elements will be more greatly subjected to their own weight and compressed together to close the interstices between said particles and express the liquid therefrom. Obviously the angle can not be much greater than the angle of repose unless additional means be provided to retain the solid mass in the scoop elements. The angle may also depend in part on the speed of the rotor, but the latter moves very slowly, say at a peripheral 55

speed of 37 to 60 feet per minute, although it may also move considerably faster or slower.

If the angle of the scoop elements be 90 degrees, the sand will build up its own angle of repose, and the comparative inactivity of the sand in said angle will not materially affect the operation of the machine. Thus regardless of the specific angle of said elements, the sand may build up a natural angle of its own.

Each of the scoop elements may have side walls 10 30, 31, aiding in the retention of the solids thereon and permitting the use of an angle substantially larger than the angle of repose. The bottom edges or blade portions of the scoop elements are suitably spaced above the floor of the 15 compartment to permit the building up of a suitable mass of settled solids. The side walls 30, 31 may be correspondingly spaced from the hub 23 and side wall 11 of the compartment respectively to afford a substantial settling space. 20

The wall 25 may include portions extending around the scoop elements, such as inner and outer peripheral portions 32, 33 and intermediate sections 34, all of which may be made of sufficiently large area, and also surround the opening 25 29. It will now be seen that the scoop elements communicate with the sections 34 at 35 and with adjacent portions of the circular zones 32, 33, particularly the outer circular zone, for discharging solids thereon.

30 For removing solids from the upper portions of the scoop elements or the wall 25, suitable stripper means may be provided, which, in a simplified form, may consist merely in a plate 36 that extends in an upright position closely along the wall 25, at an angle to a radial line of the rotor. This stripper plate may be curved as shown, in the manner of a cam, and may be stationary, being connected at one end at 37 to the settling compartment, and its other end 38 being in wiping contact with the flange 27 of the rotor hub. Disposed radially beyond the stripper plate is a discharge means such as a downwardly inclined chute or plate 39 connected to the settling compartment.

40 Connected to the settling compartment is an inlet means 40 which communicates with said compartment preferably below the level of said wall 25, and is of sufficiently large area to discharge a liquid and its finely divided solids into the compartment at a low velocity. For draining liquid from the settling compartment, an outlet means 41 may be provided so arranged as to maintain a liquid level 42 in the compartment below the level of said wall or the upper portions 50 of the scoop element.

55 The operation of the device will now be briefly described. The incoming material is distributed over a large space in the settling compartment, without disturbing the settling action. Settling may thus occur within the hub 23, and all around the scoop elements. While the settling occurs, the rotor turns, providing a gentle agitation to cause impurities and light solid materials to be loosened and flow off with the liquid through the outlet. When the settled solids build up to the level at 43, there is sufficient resistance to cause the solids to begin forcing their way up along the scoop elements which simultaneously compress the solids to drive out the water. When the solids reach the upper portions of the scoop elements, they may be removed, or may pile up on the wall 25 and be removed therefrom while being additionally compressed by the means 36 and dis- 60 65 70 75 75

charged at 39. While this is occurring the solids are compressed under their own weight due to frictional resistance both below the water level and above the same. During operations the 5 solids are maintained with upper or other large free surfaces. When the solids reach the wall 25, draining may also occur along said wall toward the center thereof, and especially while the stripper means is in operation. Such excess liquid 10 which will be comparatively little, will return to the settling edge of the rotor without disturbing the solids accumulated in the scoop elements, which may be full of sand.

By this invention, a mass of solids is subjected 15 to liquid removal over a relatively long period of time, and while several revolutions of the rotor occur. Not only is the machine as a whole continuous but each individual scoop element is continuous in its action. Therefore superior decantation 20 is obtained. The invention may be used for the separation and washing of sand or ores, and other solids, and for classification.

It will be appreciated that various changes and 25 modifications may be made in the device as shown in the drawing, and that the same is submitted in an illustrative and not in a limiting sense, the scope of the invention being defined in the following claims.

I claim:

30 1. Decantation apparatus including a settling compartment, means for feeding into said compartment a liquid containing solids to be separated therefrom, means above the bottom of said compartment for draining liquid therefrom, means in the compartment for removing the settled solids therefrom including an inclined scoop member, means for substantially constantly operatively moving said member along the settled solids with a lower portion of the member extending 35 below the upper level of the solids, the inclination of said member relative to a horizontal plane being such that the solids are caused to move up on the member to the upper portion thereof and to be compressed to expel liquids 40 therefrom due to the resistance and angle of repose of the solids and the angle of the scoop member, the upper portion of said member being above said liquid level, and means for removing the solids from the upper portion of said member.

50 2. Decantation apparatus including a settling compartment, means including a plurality of scoop elements successively movable along said compartment, said elements being elongated at an angle of less than approximately 45 degrees 55 with a horizontal plane such that the settled solids are caused to move upward along said elements and are simultaneously compressed to expel liquids therefrom, means stationary relatively to the elements for removing the solids from the upper portions of said elements as a result of the movement thereof, and means for draining the liquid from said compartment so as to maintain a liquid level below the removing means.

55 3. Decantation apparatus including a settling compartment, a rotor therein having an upright axis and a plurality of angularly spaced scoop elements, each of said elements being disposed at such an angle with the horizontal as to cause the settled solids to move upward along said elements due to movement of the latter and to simultaneously cause expression of liquids in the solids, a stripper means for removing from the successive elements the solids accumulated at the 60 upper portions thereof, inlet means for a mate-

rial to be decanted, said inlet means being provided in the casing at a side of the rotor and below the top thereof, and outlet means for liquid in the compartment, said outlet means being so arranged as to maintain a liquid level below the 65 upper portions of said elements.

4. Decantation apparatus including a settling compartment having a substantially horizontal bottom, a rotor in the compartment having a substantially vertical axis, said rotor having a plurality of angularly spaced scoop elements, each of said elements being elongated along the path of movement thereof and at such an angle with a horizontal plane as to cause the solids to be pressed upward along the elements to the upper 10 portions thereof, the lower portions of said elements being spaced from said bottom to afford settling space, means for maintaining the liquid level in the compartment below said upper portions, and means for stripping the solids from 15 said upper portions of the elements.

5. Decantation apparatus including a settling compartment, a rotor therein having a plurality of angularly spaced scoops elongated in the direction of travel thereof, each of said scoops being inclined at an angle such that the settled solids are caused to move upward thereon to the upper portions of the scoops and to be simultaneously compressed to expel liquids therefrom, a 20 floor member extending along the upper portions of the scoops and communicating therewith to receive solids therefrom, means for stripping solids from said floor member, and means for maintaining a liquid level in the compartment below the 25 floor member.

6. Decantation apparatus including a settling compartment, a rotor therein including a plurality of angularly spaced scoops each of which is inclined at a small acute angle with the horizontal plane such that the settled solids are caused to 30 be compressively moved up along said scoops, means overlying the scoops and being downwardly concaved toward the center of the rotor, said means communicating for receiving settled solids 35 from the scoops, means for stripping settled solids from the communicating means, and means for maintaining a liquid level in the compartment below the 40 low said communicating means.

7. A method of decanting solids from a liquid having a mass of settled solids therein, including 45 continuously upwardly separating from said mass, along an inclined path substantially parallel to the surface of said mass, a body of the solids while maintaining the body in contact with said mass, including adding solids from said mass to the body at a low portion of the latter so as to cause upward movement of the body with the upper portion of the body disposed above the liquid, while maintaining in the upper portion of the body a sufficient mass of decanted solids 50 to cause the weight of the latter to act on the settled solids and express liquids therefrom, due to the resistance and angle of repose of the solids, and substantially continuously removing 55 solids from the upper portion of said body.

8. A device including a settling compartment, a scoop element therein having a bottom and side walls, and the bottom wall being inclined at an angle to the horizontal, means for substantially continuously operatively moving said scoop element along a mass of settled solids in the compartment so as to cause said solids to compressively move upward along the scoop element, and means to substantially constantly maintain a liquid level in the compartment below 60

the level of the upper portion of said scoop element.

9. Decantation apparatus including a settling compartment having a liquid level, and means 5 constituting an upwardly inclined path for supporting decanted solids for upward movement therealong, including movable means confined to a lower end portion of said path for continuously compressively adding settled solids at the lower 10 end portion of said path below the liquid level for propelling the decanted solids upward along said path and above the liquid level, and so that the weight of the solids along said path causes a substantial expression of liquids therefrom.
- 15 10. Decantation apparatus including a settling compartment having a liquid level, and means therein having relative movement therewith and including a wall affording an inclined path for the movement of a continuous body of solid particles therealong, said means having a portion 20 confined to a lower end of the path below the liquid level for engaging and forcing settled solids to move upward along said path to a point above the liquid level, the inclination of said path being such that the solid particles exert a pressure on each other along the path.

11. Decantation apparatus including a settling compartment having a liquid level, and a unitary means therein having an inclined unobstructed 25 wall for the movement of decanted solids therealong, said compartment and said unitary means being rotatably movable relatively to each other, and the latter including means for continuously compressively adding settled solids to the wall at 30 a lower portion thereof below the liquid level so as to force the decanted solids upward along the wall to a point above the liquid level, and the inclination of the latter being sufficient to cause 35 the decanted solids on said wall to exert a compressive force on the settled solids received by said wall, so as to cause expression of liquids from the settled solids.

12. Decantation apparatus, including, in combination, with a settling compartment, of a scoop 40 therein coordinated for relative movement with

the compartment, the scoop being generally inclined at an angle with the horizontal less than the angle of repose whereby the solids are caused to travel up and along the scoop, receiving means in proximity to and extending substantially around the upper end of the scoop for receiving settled solids discharged thereon from the scoop, the receiving means being in relatively fixed relation to the scoop, and means for automatically removing solids from the receiving means, during 10 the relative movement between the scoop and the compartment.

13. Decantation apparatus including in combination with a settling compartment, of a scoop 15 therein coordinated with the compartment for relative rotary movement therebetween, about a substantially vertical axis, the scoop being at an angle with the horizontal approximately equal to the angle of repose of the solids, means whereby the liquid level in said compartment is maintained below the level of the upper portion of 20 the scoop, and means for removing the solids from the upper portion of the scoop.

14. Decantation apparatus including in combination with a settling compartment arranged to 25 maintain a liquid level, of an inclined scoop therein coordinated with the compartment for relative movement therebetween along a fixed path, the angle of inclination of said scoop relative to a horizontal plane being such that solids 30 are caused to move up and along the scoop to an upper portion thereof and to be compressed to expel liquids therefrom due to the resistance and angle of repose of the solids and the angle of the scoop, the upper portion of said scoop being 35 above the liquid level, means for removing the solids from the upper portion of the scoop toward one side thereof, said upper portion of the scoop being downward inclined toward the opposite side thereof for drainage of liquids, and including a 40 retaining element for the solids on the upper scoop portion, located at the last mentioned side, and said retaining element being open at the ends of the upper scoop portion.

JOHN ZOLLINGER. 45
